United States Patent Office

Des. 198,307
Patented June 2, 1964

198,307

BOOT

Sidney E. Cohn, Clarksville, Tenn., assignor to Acme Boot Company, Inc., Clarksville, Tenn., a corporation of Tennessee

Filed Jan. 8, 1964, Ser. No. 78,128

Term of patent 7 years

(Cl. D7—7)

The drawing has been lined for color.

I claim:

The ornamental design for a boot, substantially as shown and described.
